UNITED STATES PATENT OFFICE

2,095,257

LUBRICATOR FOR CAR JOURNALS

Robert C. Kendall, Chicago, Ill.

Application December 9, 1935, Serial No. 53,496

9 Claims. (Cl. 308—88)

This invention relates to lubricators for car journals. The invention has particular reference to lubricators that employ a wick for carrying lubricant to the axle, and a spring pressed wick holder serving to yieldably press the upper end of the wick against the axle.

In certain journal boxes the space between the axle and side wall of the journal box is rather limited, and one of the objects of this invention is to provide a lubricator which is capable of functioning properly in such limited space.

Another object is to simplify and to reduce the number of parts of the device. Another object is to provide a wick holder in the form of two hinged leaves, one of which is slidably mounted, and the other of which is spring pressed toward the axle whereby to press the upper end of the wick against it.

With these and other objects in view, this invention consists in the several novel features of construction, arrangements and combination of parts hereinafter fully set forth and claimed.

The invention is clearly illustrated in the accompanying drawing, in which:—

Fig. 1 is a vertical cross-section through a car journal equipped with a lubricator embodying a simple form of the present invention;

Fig. 2 is a detail, vertical cross-section through the lubricator and fragments of the box and axle, taken on the line 2—2 of Fig. 4;

Fig. 3 is a side elevation of the lubricator with its two leaves laid out flat;

Fig. 4 is a view partly in plan and partly in horizontal section, of the device and fragments of the box and axle; and

Fig. 5 is a side elevation of fragments of the wick and its wick holding strip.

Referring to said drawing, the reference character 10 designates a journal box of conventional form, in which is contained the bearing brass 11 that bears upon the car axle 12. In the bottom of the journal box is a well 9 in which is contained a quantity of lubricant.

Bolted or otherwise rigidly secured to either wall 13 of the journal box is a supporting bar 14, having a horizontal part 15, which is offset slightly from the side of the wall. The supporting bar is located somewhat below the axis of the axle.

Slidably mounted on the offset part of the supporting bar is a wick holder 16 desirably composed of two struck up sheet metal leaves 17, 18, hinged together by a horizontally extending pintle 8, and urged apart by a spring device 19 having coils 20 surrounding the pintle, and arms 21, 22 engaging the respective leaves.

Desirably the spring device 19 is composed of a single piece of resilient wire, with the two coils spaced apart and the two arms 22 connected by the part 23. The exact form of spring device, however, is not material to the invention, broadly considered.

The metal of the leaf 17 is bent up along its upper end to provide a sleeve 24, which is slidably mounted on the supporting bar, and the lower part of the leaf 17 is notched to form two spaced hinge ears 25, 25, that are bent up to provide the apertures for the pintle 8. The overlapping parts of the leaf are spotwelded together. The leaf is bent upon itself along a horizontal line between the sleeve and pintle, whereby the hinge ears 25 are made to incline toward the axle, thereby bringing the lower ends of the leaves within the space formed by the curved lower wall of the journal box.

The leaf 18 comprises a horizontal, channeled pressure plate 26, from which extends hinge ears 27 that are bent up to provide apertures for the pintle. The bent up parts are spotwelded together as shown. The upper and lower edge portions of the pressure plate 26 are bent back upon themselves to form grooves 7, in which is received a wick holding strip 28 that carries the wick 29. Preferably the pressure plate 26 and strip 28 are bent along horizontal lines midway between their upper and lower edges to make these parts slightly concave, whereby the upper part of the wick may readily conform to the curvature of the axle. A pin 33 secured at the end of the supporting bar serves to retain the wickholder thereon.

The wick 29 is comprised of suitable absorbent material and is doubled upon itself at its upper end, and the edge of the doubled over part 30 is stitched to the main body of the wick. The wick-holding strip 28 is fastened to the doubled over part 30 by staples 31, thereby leaving the face of the wick, which bears against the axle, entirely free from the staples. The ends of the wickholding strip are formed with tongues 32, bent around the ends of the doubled over part of the wick, and said ends are also formed with tongues 34 bent around the ends of the pressure plate 26 of the leaf 18 to securely fasten the wick on the wickholder. The pressure plate 26 is spaced far enough above the pintle to hold the doubled part of the wick against the side of the axle.

The pintle may fit loosely in the bearing apertures of the leaves, thereby permitting the leaf 18 to accommodate itself to any angular position the axle may assume.

The lower end of the wick is submerged in

the lubricant and carries the lubricant to the axle by capillary attraction. The spring device yieldably holds the doubled part of the wick against the axle with relatively slight pressure 5 and yields as a result of any sidewise movement of the axle in the box. The entire wickholder being slidably mounted on the supporting bar, it is free to shift back and forth along with any endwise movement of the axle relative to the 10 journal box.

It is to be observed that by reason of the shape and construction of the wickholder, the lubricator occupies but little space and can occupy an extraordinary narrow space between the side wall 15 of a journal box and the axle therein, and will function properly despite such narrow space. There are no intervening parts between the swingable wickholding leaf and the supporting leaf that prevent the wickholding leaf from assuming a 20 position contiguous with the supporting leaf.

The lubricator may, of course, be used in any situation where lubrication of an axle is required; its use is not to be understood as limited to rail- 25 way car axles.

25 I claim as new and desire to secure by Letters Patent:

30 1. A car journal lubricator, comprising in combination, a supporting bar arranged to be supported in a horizontal position on a wall of a journal box in close proximity thereto, a leaf 35 slidably mounted on said supporting bar, a swingable leaf hingedly mounted on the first mentioned leaf on a horizontal axis located below the supporting bar, a wick, means to removably secure the wick to the upper part of the swingable leaf, and yieldable means to urge said leaves apart and therewith press the upper end of the wick against an axle journaled in the journal box.

40 2. A car journal lubricator, comprising in combination, a supporting bar arranged to be supported in a horizontal position on a wall of a journal box in close proximity thereto, a leaf slidably mounted on said supporting bar, a swingable leaf having a horizontal wickholding part at its upper 45 end, a pintle hingedly connecting the lower ends of the two leaves, a wick removably secured to said wick holding part of the swingable leaf, and a spring device interposed between said leaves and serving to urge said leaves apart and there- 50 with press the upper end of the wick against an axle journaled in the journal box.

55 3. A car journal lubricator, comprising in combination, a supporting bar adapted to be supported in a horizontal position on a wall of a journal box in close proximity thereto, a leaf slidably mounted on said supporting bar, a swingable wick supporting leaf, a pintle hingedly connecting said leaves along a horizontal axis, a wick having a wickholding strip attached to its 60 upper end, said strip being removably secured to said wick supporting leaf, and a spring device interposed between said leaves, serving to urge said leaves apart and thereby press the upper end

of the wick against an axle journaled in the journal box.

4. A car journal lubricator, comprising in combination a supporting bar adapted to be supported in a horizontal position on a wall of a journal box in close proximity thereto, a leaf slidably mounted on said supporting bar, a swingable leaf having a horizontal pressure plate at its upper end, a pintle hingedly connecting said leaves along a horizontal axis below the supporting bar, a wick 10 having a wickholding strip removably seated on said pressure plate, and a spring interposed between said leaves serving to urge the leaves apart. 15

5. A car journal lubricator, comprising in combination, a supporting bar arranged to be supported in a horizontal position on a wall of a journal box in close proximity thereto, a leaf slidably mounted on said supporting bar, a swingable leaf hingedly mounted on the first mentioned leaf on a horizontal axis located below 20 the supporting bar, said swingable leaf having a horizontal slideway in its upper end, a wick, a wick supporting strip seated in said slideway, and a spring device interposed between said leaves and serving to urge said leaves apart, whereby to press 25 the wick against an axle journaled in the journal box.

6. A journal lubricator, comprising a relatively thin supporting leaf adapted to be supported on a wall of a journal box in close proximity thereto, a relatively thin wickholding leaf hingedly connected to said supporting leaf on a horizontal axis at its lower end, a wick carried by said wickholding leaf, and resilient means serving to urge said leaves apart, whereby to press the wick 30 against an axle journaled in said journal box. 35

7. A journal lubricator, comprising two up- 40 standing leaves, a horizontally extending pintle hingedly connecting the lower ends of said leaves together, a spring interposed between said leaves, means to support one of the leaves, and a wick carried by the other leaf in position to engage the side of an axle. 45

8. A car journal lubricator, comprising a horizontal supporting bar, a sheet metal wick holder 45 comprising two upstanding leaves hingedly connected together at their lower ends by a horizontally extending pintle, one of said leaves being doubled upon itself to provide a relatively long sleeve slidably mounted on said supporting bar, 50 means to urge said leaves apart, and a wick secured to the upper end of the other leaf. 55

9. A car journal lubricator, comprising a horizontal supporting bar, a sheet metal wick holder 55 comprising two upstanding leaves hinged together at their lower ends, and one doubled upon itself to form a relatively long sleeve slidably mounted on said supporting bar, the other leaf being formed with a concave pressure bar, means to urge said leaves apart, and a wick secured to the concave side of the pressure bar, whereby the wick may conform to the curvature of an axle. 60
